UNITED STATES PATENT OFFICE.

JAMES R. STULL, OF LOS ANGELES, CALIFORNIA.

ANVIL ATTACHMENT.

1,088,742.

Specification of Letters Patent.

Patented Mar. 3, 1914.

Application filed June 18, 1912. Serial No. 704,313.

To all whom it may concern:

Be it known that I, JAMES R. STULL, a citizen of the United States, and a resident of Los Angeles, in the county of Los Angeles and State of California, have invented a new and Improved Anvil Attachment, of which the following is a full, clear, and exact description.

My invention relates to anvils, and it has for its object to provide an attachment for an anvil having an arm, which extends through an opening in the top of the anvil, the arm being provided with a head, which projects longitudinally of the anvil at opposite sides of the arm, the arm being pivoted to a lever, fulcrumed to the anvil block, so that this lever may be operated by the foot of the smith, to conveniently clamp the member between the head and the anvil.

Another object of the invention is to provide means for conveniently securing the anvil to the anvil block.

Still other objects of the invention will appear in the following complete specification, in which the preferred form of the invention is disclosed.

In the drawings similar characters of reference indicate corresponding parts in both the views, in which—

Figure 1 is a perspective view of an anvil provided with my attachment; and Fig. 2 is an enlarged end view of the said anvil provided with my attachment.

As my attachment is constructed it may be used for bending, offsetting and holding metal, the attachment acting as a vise to assist a smith in bending and twisting iron in almost any manner or shape, it being possible, with my attachment, for a smith, without a helper, to bend at right angles a steel bar three inches by one inch (3"x1") in one heat, which it is quite impossible to do unless the attachment disclosed in this application is used to assist the smith.

By referring to the drawings it will be seen that on the anvil block 5 there is disposed the anvil 6, this anvil 6 having the usual flanges 7. Through the anvil block 5 there is an opening 8, through which is disposed a bar 9, this bar 9 projecting beyond the sides of the anvil block 5, and being provided with two orifices at each terminal, these two orifices 10 at each terminal being disposed substantially at right angles to each other. Through these orifices are disposed the threaded terminals 11 of the U-

shaped holding members 12, these U-shaped holding members 12 being disposed over the flanges 7, with their threaded terminals disposed through the orifices 10, so that when 60 the threaded terminals are engaged by the nuts 12^a, and the said nuts are turned home, the nuts will press against the terminals of the bar 9, and will hold the U-shaped members down and against the flanges 7 of the 65 anvil 6, by which means the anvil 6 will be held securely in position on the anvil block 5.

Through the opening 13 in the flange 14 of the anvil 6 there is disposed an arm 15, 70 the upper terminal of this arm 15 being provided with a head 16, which projects in opposite directions and longitudinally of the top of the anvil 6, so that either projection of the head 16 may engage the 75 top of a piece of iron 17, which is being worked to press the said piece of iron against the flange 14 of the anvil 6, and, in this way, hold it securely in place while the piece of iron 17 is being worked by the 80 smith. The lower terminal 18 of the arm 15 is disposed through a slot 19 in a lever 20, and in this lower terminal 18 of the arm 15 there is an orifice, which is in alignment with the orifice 21 in the lever 20, the 85 said orifice 21 extending to the slot 19. The arm 15 is articulated to the lever 20, by the pin 22, which is disposed through the orifice 21 in the lever 20, and the orifice in the lower terminal 18 of the arm 15. To prevent the 90 pin 22 from working out of position, the lever 21 is provided with a spring member 23, which presses on the head of the pin 22, and serves to hold the pin in position. In order that the pin 22 may not become lost 95 when it has been moved from the orifice, it is connected with one of the U-shaped members 12 by means of a chain 24. The lever 20 is pivoted to the anvil block 5 by means of a pin 25.

When the anvil 6 has been firmly secured to the anvil block 5 in the manner described, the arm 15 is disposed through the opening 13 in the flange 14 of the anvil, and in the slot 19 of the lever 20, the lever 20 having 100 been previously disposed with its orifice 26 in registry with the pin 25 so that when the lever 20 is moved toward the anvil block 5 the pin 25 will enter the orifice 26 in the lever 20. After this has been done the pin 105 22 is disposed through the orifices in the lever 20 and the lower terminal 18 of the

arm 15, after which the spring 23 is released, to engage the pin 22 and hold the pin in place.

It will readily be understood that when the lever 20 is moved upward by the foot of the smith, the head 16 will be raised, to permit of the insertion of a piece of iron 17, between one of the projections of the said head 16 and the anvil 6. As the head 10 projects longitudinally of the top of the anvil 6, it is possible to secure the piece of iron, which is being worked transversely of the anvil, which permits the smith to bend the piece of iron on the anvil at either side 15 of the head 16 in many different ways. In fact, with this attachment it is possible for the smith without a helper to bend the piece of iron which is to be worked in practically any manner desired.

20 As a locking means for the lever 20 I provide a curved arm 27 with teeth 28, this arm 27 being pivoted to the lever 20 at 29, and having a bent terminal 30 which extends up and through an opening 31 in the lever 20, so that the terminal 30 may be pressed down by the foot after the lever has been moved down to the desired position by the foot of the smith. This curved arm 27 passes through a slot 32 in a strap 33, the 25 outer lower end of which is held in position relatively to the anvil block 5 by a pin 34 which meshes in threaded openings in the strap 33 and in the anvil 6. It will therefore be seen that when the terminal 30 is 30 pressed down the curved arm at the teeth 28 will be moved up, and that the said teeth will engage the strap at the top of the slot to hold the lever 20 in place. To free the lever 20 or the piece of iron 17 when the 35 locking means is in use all that it is necessary to do is for the smith to put pressure on the lever 20, and the weight of the arm 27 causes the arm to drop and disengage it from the strap 33, freeing the piece of iron 17, as soon 40 as the lever 20 is raised.

Having thus described my invention I claim as new and desire to secure by Letters Patent:

1. In an anvil having a member, a head 50 for moving vertically to clamp a member to the anvil, a lever pivoted adjacent the bottom of the anvil, means by which the head may be operated by the lever, and an arm pivoted to the lever, the arm having teeth 55 for engaging the first member.

2. In an anvil having a member for engagement by teeth, a head for moving vertically to clamp a member to the anvil, a lever pivoted adjacent the bottom of the 60 anvil, means by which the head may be operated by the lever, an arm pivoted to the

lever and curved around the fulcrum of the lever, the arm having teeth for engaging the first-mentioned member for holding the lever against movement. 65

3. An anvil having a strap for engagement by teeth, a head for clamping a member to the anvil, a lever fulcrumed relatively to the anvil, means by which the head may be operated by the lever, an arm pivoted to 70 the lever and disposed in the strap, the arm having teeth for engaging the strap for holding the lever against movement.

4. In an anvil, a member for engagement by an arm, a head for clamping a member to 75 the anvil, a lever disposed below the first-mentioned member, means by which the head is operated by the lever, and an arm pivoted to the lever and curved around the fulcrum of the lever, the arm having a surface for engaging the first-mentioned member, for holding the lever against movement, the arm having a surface adjacent the lever for the purpose specified. 80

5. In an anvil, a member for engagement 85 by an arm, a head for clamping a member to the anvil, a lever having an opening, means by which the head is operated by the lever, an arm pivoted to the lever, and having a surface for engaging the first-mentioned 90 member for holding the lever against movement, the arm having a terminal extending through the opening in the lever for the purpose specified.

6. In an anvil, a member adapted to be 95 engaged by an arm, a head for moving down to clamp a member to the anvil, a lever disposed below the first-mentioned member and pivoted to the anvil, means by which the head may be operated by the lever, and an 100 arm carried by the lever for engaging the first-mentioned member for holding the lever against movement.

7. In combination with an anvil having an opening through its top, an arm disposed 105 in the opening and having a head which projects beyond the arm, there being an orifice in the arm, a lever fulcrumed relatively to the anvil and having an opening in which is disposed the arm at the orifice, 110 the lever having orifices leading to the opening, a pin disposed in the orifices in the lever, and the orifice in the arm, and a spring on the arm for engaging the pin for holding the pin in position. 115

In testimony whereof I have signed my name to this specification in the presence of two subscribing witnesses.
